United States Patent

Des. 238,556

Patented Jan. 27, 1976

238,556

ROE POUCH

Earl B. Jackson, P.O. Box 1485, Boise, Idaho 83701,
and Ray Dunlap, 1903 Washington Ave., Caldwell,
Idaho 83605

Filed Sept. 24, 1973, Ser. No. 399,880

Term of patent 14 years

Int. Cl. D9—05

U.S. Cl. D9—184

FIG. 1

FIG. 2

FIG. 3

FIG. 1 is a top left perspective view of a roe pouch showing our new design, the opposite side being substantially the same;

FIG. 2 is a right edge elevational view; and
FIG. 3 is a top plan view.

We claim:

The ornamental design for a roe pouch, substantially as shown and described.
